PAD AND HOLDER THEREFOR

Application filed December 19, 1927. Serial No. 241,029.

This invention relates to pads and holders therefor, and is more particularly related to a pad of special construction adapted to be held within a holder having gripping means 5 to secure the pad in a manner to prevent the pad from being easily removed from the holder.

In providing pads and holders therefor such, for example, as are adapted for use in banks, offices, stores and the like, the principal problem is to provide a pad and holder therefor which will leave all of the surface of the paper of the pad for use, will still lock the pad to the holder to prevent the easy removal 15 of the pad from the holder, and will also permit the individual sheets of paper to be torn from the pad without tearing the sheets as they are removed. It is essential that the holder be inexpensive in construction and 20 adapted to hold a pad securely to prevent its removal from the holder in any direction until all of the paper of the pad has been used up. The difficulty encountered in providing such a holder is that the pads of paper are 25 subject to buckling which shortens the distance between the edges of the pad, permitting the pad to fall or be easily removed from the holder. In order to provide a holder which will permit the entire surface of the 30 pad to be utilized, it is necessary that the pad of paper be gripped from its sides. If gripping means are provided which extend into the paper of the pad, it is not possible to remove the individual sheets of paper from the 35 pad without tearing the same.

In the provision of a pad for use in a holder embodying this invention, it is essential to the most efficient operation that the pad be secured together at the upper edge of the sheets 40 of paper by means of a glue and material which will form a stiff, brittle back from which the sheets of paper may be easily removed without tearing the same at the upper edge. It is also essential that the pad of paper be mounted upon a relatively stiff back 45 in order to prevent buckling of the individual sheets of paper to less than their width and permit the sheets of paper to be withdrawn or fall from the holder.

It is, therefore, an object of this invention

to provide a holder for a pad of paper which includes means for gripping the pad at the edges thereof, which means include plates having serrated surfaces providing sharp, short teeth which extend from the surfaces a 55 relatively short distance and are of a length insufficient to actually extend into the sheets of paper of the pad and which provide sharp cutting edges from their under-most side which will cut the sheets of paper as they are 60 drawn from the pad to permit the individual sheets of paper to be withdrawn from the pad without tearing the sheets of paper but extending sufficiently from the faces of the plates to grip the pad to prevent its withdrawal both vertically and horizontally from the holder.

Another object of this invention is to provide a holder for pads of paper which includes a back having upwardly extending 70 plates spaced apart a distance equal to the width of the pad of paper to be held thereby, the plates having a multiplicity of closely associated teeth extending from their surfaces a relatively short distance.

Another object of this invention is to provide a pad of paper which may be used for any desired purpose and which is formed of a multiplicity of sheets of paper of equal width secured together by means of glue and a binding fabric at their upper end, the glue being of a nature to dry to form a brittle, stiff back and the sheets of paper being secured by said back to a relatively stiff cardboard.

Another object of this invention is to provide a holder adapted to grip pads of paper of different widths and including a back to which spaced gripping plates are adjustably secured, the gripping plates providing serrated gripping surfaces, each of which surfaces includes a multiplicity of closely associated, outwardly struck, sharp gripping teeth which are relatively short in length.

Another object of this invention is to provide a holder for a pad of paper including a back having an opening therein into which a portion of the cardboard back of the pad is adapted to fit to hold the pad from being withdrawn longitudinally of the holder.

Another object of this invention is to pro-

vide a pad of paper including a cardboard back divided upon a perforated line to permit part of the back to be torn away and the remainder of the cardboard back to be fitted 5 within an opening formed in the back plate of a holder to hold the pad from being withdrawn longitudinally of the holder.

Another object of this invention is to provide a pad of paper formed of a multiplicity 10 of sheets of paper secured together by means of glue and a fabric at their upper edge, the pads of paper being secured by the glue and securing the fabric to a cardboard back having a perforation therein into which a projection formed to extend upwardly from the back plate of a holder is adapted to fit to prevent longitudinal movement of the pad of paper relative to the holder.

Other objects and advantages of this invention, it is believed, will be apparent from 20 the following detailed description of a preferred embodiment thereof, as illustrated in the accompanying drawings.

In the drawings:

25 Figure 1 is a perspective view of a pad holder embodying this invention.

Figure 2 is a perspective view of a pad as embodied in this invention.

30 Figure 3 is a magnified fragmental view of one of the gripping plates illustrating the manner and form of gripping teeth embodied therein.

Figure 4 is a perspective view of the preferred embodiment of this invention.

35 Figure 5 is a sectional edge elevation taken substantially on the line 5—5 of Figure 4.

Figure 6 is a sectional elevation taken substantially on the line 6—6 of Figure 4.

40 Figure 7 is a sectional edge elevation similar to Figure 5 of a modified form of pad holder and pad embodying this invention.

Figure 8 is a rear elevation of a pad embodied in the modified form of this invention shown in Figure 7.

45 Figure 9 is a sectional edge elevation similar to Figure 5 of a third modified form of pad holder embodying this invention.

Figure 10 is an edge elevation of the modified form of pad employed in the holder illustrated in Figure 9.

50 In the holder embodying this invention, 1 indicates a back adapted to grip and hold a pad 2. The holder has vertically extending plates 3 and 4 preferably stamped out of the back 1 and a top stop member 5 likewise preferably stamped out of the back 1. The plates 3 and 4 are provided with means for gripping the pad 2 of paper at its edges 6 and 7 to hold the pad from vertical and longitudinal movement relative to the back 1 and to hold the pad in a manner to permit the entire surface of each sheet of paper to be utilized, and also in a manner to permit the individual sheets of paper to be withdrawn 60 from the pad without tearing the sheets of

paper and in order to accomplish these objects, the faces of the plates 3 and 4 are provided with rough surfaces preferably consisting of a multiplicity of closely spaced, fine sharp teeth 8 which are formed preferably by pressure of a die producing irregularities confined to the surface of the plate.

These teeth have their lower edges 9 sharp so that as the individual sheets of paper are withdrawn from the pad, the cutting edges 70 9 will cut the edges of the individual sheet but will not tear the same. The teeth 8 are relatively short, being preferably of a length

not to exceed $\frac{1}{16}$ of an inch. Teeth of this length do not actually project into the edge 75 of the pad but merely act to grip the edges of the individual sheets of paper of the pad to hold the pad against vertical and longitudinal movement relative to the back 1.

The serrated edges of the plates 3 and 4 are formed with the multiplicity of teeth 8 by 80 means of a die or tool which is engaged with the faces of the plates 3 and 4 on an angle so that the teeth are struck upwardly from the faces of the plates 3 and 4 and as the tool

or die used is relatively sharp, the teeth as 85 they are struck upwardly are formed with the sharp edges 9. The plates 3 and 4 are spaced apart a distance on the back 1 so that their faces are a distance away from one another equal to the width of the pad 2. The teeth 8 project inwardly from the plates 3 and 4 to grip the pad.

90 The pad 2 is preferably constructed of a multiplicity of sheets of paper which are secured to a cardboard back 10 by means of a glue and packing fabric secured to the upper edges 11 and 12 of the individual sheets of paper and cardboard 10, respectively.

The glue used in securing the gripping fabric and also for securing the individual sheets of paper to the cardboard 10 is preferably what is known as "book binder's ground bone glue" which dries extremely 95 hard or stiff, thereby insuring that the sheets of paper may be withdrawn from the pad 2 without tearing the upper edges of the same.

In order to prevent the pad 2 from buckling between the plates 3 and 4 and thereby becoming loose in the holder, the cardboard 10 100 is preferably formed of a relatively thick cardboard which will not easily buckle and this thick cardboard will not be buckled under the slight depression caused by the relatively short teeth 8 formed on the inner surfaces of the plates 3 and 4.

105 In the preferred form of this invention illustrated in Figure 4, the holder is provided with means for compensating for pads of different widths, and is preferably constructed of a back 1a to which guide brackets 14a are secured by means of screws 15a.

Plates 3a and 4a are formed of individual pieces of metal bent at substantially right angles and having their horizontally extend-

ing portions 16a extending through the brackets 14a to permit the plates 3a and 4a to be adjusted inwardly toward each other. I provide suitable means for exerting a 5 clamping force on one or both of the clamping plates to clamp the pad between them. A plug 17a is screw-threaded in each of the upwardly extending portions 18a of the brackets 14a. The plugs engage the outer 10 surfaces of the plates 3a and 4a to permit the same to be clamped against the edges 6a and 7a of the pad 2a. The serrated gripping surfaces of the plates 3a and 4a are formed in a manner exactly similar to that heretofore described, the plates 3a and 4a being provided with teeth 8a having sharpened edges 9a. In order to provide an upper stop 15 in this construction of holder, a curved plate 19a is secured to the brackets 14a by means of the upper screws 15a which pass through eyes 20a formed integral with the curved plate 19a. The curved plate is curved upwardly at its outer edge to provide a holder for a pencil, pen, or the like, as illustrated at 21. The pad 2a used in this holder is preferably similar to the pad 2. The plugs 17a are provided with hexagonal key receiving recesses 22a into which a key 23a having a hexagonal head 24a is inserted in order to 30 clamp the pad 2a in position.

In the modified form of this invention, illustrated in Figure 7, the holder is of substantially the same construction as illustrated in Figure 1 so that the same numerals have been applied thereto, with the addition of an exponent "b", with the exception that the back 1b in this modified form is provided with an upwardly projecting key 14b which is stamped from the back 1b and extends vertically upward from the back 1b to pass through an opening 15b formed through the cardboard back 10b of the pad 2b. The key 14b is provided for the purpose of preventing accidental or intended removal of the 40 pad 2b from the holder by drawing the pad 2b from between the holding plates 3b and 4b.

In the third modified form of this invention, the holder is similar to that illustrated in Figures 1 and 7 with the exception that intermediate the back 1c a pad 2c is interposed an intermediate cardboard 23c through which the plates 3c and 4c and the back stop 5c extend. Between the plates 3c and 4c and back stop 5c, the cardboard 23c is cut away to provide a rectangular slot into which the upper rectangular portion of the cardboard back 10c of the pad 2c is fitted to hold the pad 2c from being moved longitudinally of the 55 holder. The pad 2c is provided with a complete back 10c which is perforated on a line 24c to permit the lower portion 25c thereof to be torn away when it is desired to insert the pad in the holder. The upper portion 26c of the back 10c then fits within the rectangular

slot formed between the members 3c, 4c, and 5c and engages the edges of the intermediate cardboard 23c, preventing removal of the pad 2c from the holder.

Having fully described my invention and several modified forms which the same may take, it is to be understood that I do not wish to be limited to the modifications or forms herein set forth, but my invention is susceptible of alteration without departing from the scope thereof as defined in the appended claims.

I claim:

1. A pad holder including a base, a pair of jaws mounted upon said base, and means secured to the base for pressing said jaws toward each other to compress the leaves of a pad edgewise between the inner side faces of said jaws, said jaws being imperforate and having a plurality of fine teeth formed by 80 irregularities confined to the surfaces of the jaws.

2. A pad holder comprising a base having a pair of brackets secured thereto, gripping plates adjustably mounted in said brackets, and means secured to the brackets for moving said jaws toward each other to clamp a pad to the plate.

3. A pad holder comprising in combination a base, having a pair of brackets secured thereto in spaced relation to each other, gripping plates adjustably mounted in said brackets, the gripping plates having gripping teeth providing under-cutting edges and extending from the opposed surfaces of 95 said gripping plates, and means on said back intermediate the gripping plates for engaging the bottom of the pad mounted between the gripping plates.

4. A pad holder including a back having a 100 pair of spaced guide brackets secured thereto, a gripping plate adjustably mounted in each guide bracket, the gripping plates including substantially horizontal portions slidably mounted in said guide brackets, and substantially vertically extending sections, and means secured to the guide brackets and engageable with the vertically extending portions of the gripping plates to adjust the latter said portions toward each other.

5. A pad holder including a back, a pair of spaced brackets secured to the back, a gripping plate slidably mounted in each bracket, each gripping plate having a gripping portion extending from the plate at 110 substantially right angles for gripping the edge of the pad, and a screw plug screw-threaded to each bracket and engaging each gripping plate to force said gripping plates into clamping relation to a pad.

6. In a pad holder for holding a pad composed of superposed sheets attached together along one end, the combination of a back plate, a pair of spaced gripping plates extending upwardly opposite to each other 120

with their opposed faces substantially at right angles to the plane of the back plate, said gripping plates having their adjacent faces formed with a plurality of relatively fine projections formed on and confined to their inner surface and pressing against the sides of the pad to clamp the same, and operating to hold the pad without interfering with the removal of the top sheet of the pad.

10 7. In a pad holder of the kind described, the combination of a plate having a pair of oppositely disposed gripping plates, the opposed faces of the gripping plates having outwardly extending gripping teeth formed by irregularities confined to the said adjacent faces of said gripping plates, said gripping plates co-operating to hold a pad of paper gripped between the gripping plates, and means for exerting force for forcing the 15 gripping plates toward each other to grip the edges of the pad, said gripping plates co-operating to hold the pad without interfering with the removal of the uppermost sheet of the pad to be removed.

20 8. In a pad holder for holding a pad composed of superposed sheets connected together at one end, the combination of a back plate, a pair of spaced gripping plates extending upwardly opposite to each other and 25 connected along their lower edges with the back plate and projecting substantially at right angles to the plane of the back plate, said gripping plates having their opposed faces formed with a plurality of relatively fine projections for engaging the edges of 30 the sheets composing the pad.

35 9. A pad holder for holding a pad composed of superposed sheets attached together at one end, including a back, a pair of solid gripping plates mounted thereon and extending substantially vertically upward from said back, the gripping plates being formed with a multiplicity of relatively short fine gripping teeth consisting of irregularities on 40 the surface of the plates and having sharp edges operating to grip the sides of the pad and hold the same in place without interfering with the removal of the uppermost sheet of the pad.

45 10. A pad holder including a back, a pair of spaced gripping plates extending from said back at substantially right angles, a back stop formed from said back between the gripping plates, the plates having gripping 50 means on their opposed surfaces, said gripping means including a multiplicity of closely spaced teeth formed by irregularities on the surface of the plates, and having sharp undercutting sides for engaging the edge of the 55 pad and holding the same in position without interfering with the removal of the uppermost sheet of the pad.

60 11. In a holder for a pad of paper having a stiff bottom sheet, the combination of a back, a pair of spaced gripping plates ex-

tending from said back with inner faces at substantially right angles to the plane of the back, the gripping plates having gripping means upon their said inner surfaces for engaging the sides of the pad, and means on said back for engaging the said stiff bottom sheet of the pad.

Signed at Los Angeles, California, this 30 day of November, 1927.
